UNITED STATES PATENT OFFICE.

L. SANDIDGE ALLISON, HARRY JOHN, AND THOMAS E. EVANS, OF HAZLETON, PENNSYLVANIA.

STEAM-ACTUATED VALVE.

SPECIFICATION forming part of Letters Patent No. 274,247, dated March 20, 1883.

Application filed December 14, 1882. (No model.)

To all whom it may concern:

Be it known that we, L. SANDIDGE ALLISON, HARRY JOHN, and THOMAS E. EVANS, all of Hazleton, in the county of Luzerne and State 5 of Pennsylvania, have invented certain new and useful Improvements in Steam-Actuated Valves for Steam-Pumps, of which the following is a full, clear, and exact description.

The object of the invention is to prevent 10 the main valve from striking at the end of its stroke and to regulate the speed of its operation, so that the pump-valves shall seat themselves without jar, all as hereinafter described and claimed.

15 Reference is to be had to the accompanying drawings, forming a part of this specification, in which similar letters of reference indicate corresponding parts in both the figures.

Figure 1 is a longitudinal section of a steam-20 cylinder with our improved valve mechanism, and Fig. 2 is an end elevation of the same.

A represents a steam-cylinder of a direct-acting pump, and B the piston-head or plunger.

C is the steam-chest, containing a slide-valve, 25 a, fitted for movement by pistons b b. The cover of the chest C is formed with steam-passages c c for admission of steam behind the pistons b, and also with an exhaust-passage, d, and is also formed as a seat for a slide-valve, e, of ordinary character, that is contained within a secondary steam-chest. The stem f of the valve e, passing through one side of the steam-chamber, is connected to one end of a lever, g, which is hung upon the outer end of the valve-stem h of the main valve a. Through 30 a stuffing-box in the head of the main cylinder A extends a slide-rod, i', the inner end of which projects into the cylinder a sufficient distance to be struck by the piston B, when 40 the latter reaches near the end of its stroke, so that the outer end of the rod i will strike the lower end of the lever g. The arrangement will be the same at each end of the steam-cylinder A, but is only shown at one end in 45 the drawings.

The valves being in position as shown, and

piston B, moving in direction of its arrow, comes in contact with rod i, and moves valve e in direction of the arrow until arrested by stop k, when the main valve a will be moved to the 50 middle position by the continued movement of lever g. The pump will then stop until the steam, acting on one piston b of valve a, completes the throw of that valve. This last movement carries lever g to its outward position, 55 (shown by dotted lines,) and places the corresponding lever at the other end of the cylinder in the inner position for being moved by return of plunger B.

The exhaust-passage d of the secondary 60 steam-chest connects, as shown by dotted lines in Fig. 2, with the main exhaust l, and in this passage is fitted a valve, m, arranged for movement by a hand-wheel, n, for regulating the exhaust from the main valve, so that 65 it may be made to move more or less gradually in order to cushion the valve and give time for the pump-valves to seat without jar.

We are aware that it is not new to use a 70 knocker on the rod which connects the pistons of a steam and a pump cylinder for the purpose of actuating a slide-valve, or to operate a steam-chest valve by a slide-rod, (passing through the chest,) levers, and pins, the latter 75 passing into the steam-cylinder and moved by the piston thereof; but

What we do claim as new and of our invention is—

The combination, with the rods i, movable in the steam-cylinder A, and the levers g, bearing with one end against said rods, of the valve-stem f, pivoted to the other end of said lever, and the main-valve stem h, pivoted to said lever between its ends, whereby the valves of the main and auxiliary chests will be operated, as described.

L. SANDIDGE ALLISON.

HARRY JOHN.

THOMAS E. EVANS.
